LABELING MACHINE

Aristides Poggio, Zárate, Buenos Aires, Argentina

Application May 17, 1940, Serial No. 335,851

8 Claims. (Cl. 216—55)

The present invention relates to machines for labeling containers and in particular for applying labels to containers having the shape of a truncated pyramid.

In general the object of the invention is to provide a labeling machine which shall perform automatically all the steps necessary for the labeling of containers which are of prismatic or frusto-pyramidal shape and have a rectangular base.

A further object of the present invention is to provide a machine of the type described which shall have its parts so constructed and arranged as to enable it to produce in a simple and efficient manner satisfactorily labeled containers and to require a minimum of supervision and that of a very simple order, while being economical to run and relatively cheap to construct.

My novel machine comprises essentially a frame carrying an outer and an inner endless conveyor arranged to run in synchronism, the outer conveyor having secured thereto a plurality of receptacles, said frame likewise carrying driving means for said conveyors and supporting at one end a label holder, and transfer devices comprising an assembly adapted to remove labels from said holder and place them in said receptacles and an assembly adapted to remove containers one by one from a runway or chute and place them in said receptacles on top of said labels, said receptacles being provided with movable gripping means for holding the container and the label, and the inner conveyor being provided with a plurality of pairs of label wiper brushes, yieldably connected together and adapted to pass through the outer conveyor to apply the labels firmly against the sides of the containers, the machine including likewise adhesive applying means and means for actuating the movable gripping means.

The transfer device includes suction devices comprising a label lifter secured to a label transfer member, and a can lifter mounted on a can transfer member, said members being oscillated between two end positions by means of cranks driven from the main or outer conveyor.

In the drawings:

Fig. 1 is a side elevation of a labeling machine according to the present invention.

Fig. 2 is a perspective view of a label lifter device.

Fig. 3 is a perspective view of a hinged guide-way forming part of the label lifter.

Fig. 4 is an elevation of a can lifter.

Fig. 5 is a perspective view of a suction cut-off.

Fig. 6 is a side elevation of a can feeding and 55

gumming assembly mounted on the end of the machine frame.

Fig. 7 is a perspective view of half of a can carrying receptacle.

5 Fig. 8 is an elevation of a label wiper device.

Fig. 9 is a plan view of the machine.

The can labeling machine according to the present invention consists of a frame 10 which supports an outer endless conveyor 12 which 10 passes round a double set of chain wheels 14 so arranged that the conveyor follows a polygonal path. Inside the space defined by the outer conveyor 12, there is provided an inner endless conveyor 16 which runs round chain wheels 18. The 15 two conveyors are run in synchronism by means of transmission chain 20 and the chain wheels 22 and 24. The conveyors may be driven by any suitable means as, for example, a belt drive from a source of power to a pulley (not shown) or a direct-coupled motor.

At one end 10' of the frame 10, is located a transfer device which comprises a label removing assembly 26 and a can removing assembly 26'. The label removing assembly 26 consists of a 25 swinging arm 28, a pivoted arm 32 and a link 30 connecting these two arms. The arm 32 is pivoted to one frame member 10a at 36, and the swing arm which is slotted as shown, is adapted to swing about and slide relatively to a pin 34 fast 30 on said frame member 10a, said pin 34 being at a point on the frame member between said pivot 36 and the nearest end of the outer conveyor. The end of the swinging arm 28 remote from the link 30 is connected to an adjustable throw crank 35 actuating device comprising a bar 38 coupled at one end to the arm 28 by means of a slidably and rotatable member 40 and at the other end is pivotally secured to a cross-head 41 slidably adjustable in a diametrical groove 43 in a disc 42 driven 40 by the outer conveyor 12.

The construction of the can removing assembly 26' is the same up to this point, and the corresponding parts have been marked with primed reference numerals in the drawings. The pin 34' 45 for arm 28' corresponding to pin 34 of arm 28 is fast on the frame member 10b parallel to the member 10a and on the opposite side of the frame. Similarly, an adjustable throw crank, corresponding to the crank 42 and adapted to actuate the arm 28' of the can removing assembly, is mounted on the frame member parallel to the member 10 on the opposite side of the machine.

50 This arrangement of parts will cause the linked ends of the swinging arms 28, 28' to oscillate in a curved path the parts being so proportioned

that one end of said path coincides with a position to which successive receptacles carried by the outer conveyor and to be hereinafter described are brought by advance of the conveyor 12, and the other end of the path lies in the case of arm 28' over the delivery end of a can chute 46 and in the case of arm 28 over a label holder 44 provided at said end 10' of the main frame.

The eccentrics or cranks 42 are arranged 180° out of phase so that when the linked end of the label lifter arm 28 is at one end of its path the corresponding end of the can lifter arm 28' is at the opposite end of its path. The can lifter arm 28' is longer than the label lifter arm 28, and since their motions are 180° out of phase, it will be clear that when the cranks have rotated half a revolution from the position shown in Fig. 1, the can lifter arm will have moved to its position over the chute 46 (hereinafter called its rearward position) and the label lifter arm 28 will have moved to its position over the conveyor 12 (hereinafter called its forward position). The receptacles are so distributed on the conveyor that at the moment just described a receptacle will have been brought by the conveyor 12 to a point just below the label lifting device carried by arm 28, and that on rotation of the cranks through a further half revolution, the receptacle will have been advanced a distance so as to bring it below the can lifting device carried by arm 28' which will then be in its forward position.

As just indicated, the arm 28 carries a label lifter 48 and the arm 28' carries a can lifter 50. Both these lifting devices are designed to operate by suction and will now be described with particular reference to Figs. 2, 3 and 4.

According to the embodiment shown in Fig. 2, the label lifter 48 comprises a tubular substantially L shape member 49 the bar of which forms a suction mouth 51' of circular cross-section and the leg of which communicates with the interior of a second suction mouth 51 of rectangular cross-section, the extremity of which lies in the same plane as the extremity of the suction mouth 51'. At a point intermediate the ends of the leg portion of member 49 there is provided a connection pipe 52 which is preferably directed away from the plane of the suction mouths and is adapted to receive a suction hose 53 of flexible material, as for example, rubber. A guide bar 54 carrying an adjustable stop collar 56, extends from above the suction mouth 51 and is adapted to pass slidably through a support 55 rotatably secured to the label lifter arm 28. Projecting laterally from the suction mouth 51 are a pair of pins 57 carrying at their free ends rollers 58 adapted to run on inclined surfaces 63, 63' of a guideway 60 (Fig. 3) hingedly attached to a support 61 (Fig. 1) rising from the main frame 10. Said guideway is mounted a convenient distance above the label carrier 44 and comprises a pair of legs 62, 62' connected together at one end by a base portion 64 from which lugs 64a project drilled to provide holes 65 for the passage of the hinge-pin (not shown). The inclined surfaces 63, 63' are not co-extensive with the legs 62, 62' so that there is formed in the neighbourhood of the base 64 a rectangular opening 66 adapted to allow the rectangular suction mouth 51 and the pins 57 of the label lifter to pass freely therethrough.

The above described arrangement or its equivalents have been found necessary as otherwise the label lifter will not sit flat on the pile of labels nor will its mouths be directed downwardly at

both ends of the stroke of arm 28. Considering the backward stroke of the arm 28, the label lifter will be brought to the free ends of the leg portions of the inclined guideway and the then 5 downwardly moving arm will cause the rollers 58 to engage the surfaces 63, 63' so that the movements of the label lifter will be constrained with respect to the arm. Further swinging movement of the arm will cause the label lifter to be 10 pushed along the inclined surfaces 63, 63' and the head of support 55 will move down the guidebar 54, the support turning on its axis to allow of the necessary small turning component. The arrangement is such that when the arm 28 is just 15 about to reach the end of its backward stroke, the rearward end of the label lifter will have reached the opening 66 so that the whole lifter will drop, the guide-bar 54 sliding through the head of the support 55 until stopped by the collar 20 56, which is so adjusted that the stoppage occurs when the arm 28 has reached the end of its stroke and the label lifter has contacted with the uppermost of the pile of labels which rests on the label carrier 44. As the arm 28 commences 25 its forward stroke, it raises the label lifter which has picked up a label and brings the rollers 58 into contact with the under side of the surfaces 63, 63'. Inasmuch as the end of the arm 28 carrying the label lifter rises, it will 30 cause the guide-way 60 to be lifted on its hinge until the rollers 58 have cleared the free ends of the leg portions 62, 62' the guideway thus helping gravity to keep the label lifter in position with its mouths directed downwardly. Thereafter the 35 guide-way will drop back into its original position.

The can lifter as shown in Fig. 4 comprises a mounting arm 70 having at one end means 72 for securing it rotatably to the can lifter arm 40 28' and formed at the other end to provide a sucker 74 the plane of the mouth 76 of which is inclined to the axis of said mounting arm. The sucker 74 is connected to a suction pipe 78, for example, by means of a screw 80. 45 Each of the arms 28, 28' carries a suction cut-off 82, 82', one embodiment of which is shown in slightly exploded form in Fig. 5 and the purpose of which is to cut off and cut in the suction at predetermined points in the strokes of the arms. 50 As shown in Fig. 5, the cut-off consists of a hollow support 84 one end of which carries fixing means 86 for fixing the cut-off to the respective arm 28 or 28', and the other end of which has a coupling plate 88 for coupling the 55 cut-off mechanism to said hollow support. Said support is provided with tubular branches 90 and 92 adapted to receive the suction pipe 53 or 78 communicating with the label or can lifter, and the suction trunk 94, 94' running to the 60 suction producing device (not shown). The cut-off mechanism comprises a perforated disc 96 adapted to be fixed to the plate 88 and provided with a pin 108. Through the disc 96 and into the interior of the hollow support 84 passes a tubular rotatable valve member 98 having orifices 97' and 97 adapted in the operative or sucking position of the device to the register with the branches 90 and 92 respectively. The outer 65 end of the valve member 98 is closed by a head 100 from which project a cut-off finger 102 and an admission finger 104, said head being also provided with projecting stops 106, 106', adapted to limit the rotation of the valve member by engagement with the pin 108 between which and 70 75

a suitable point on the head 100 a dead centre spring 110 is stretched.

The label carrier 44 (Figs. 1 and 6) the purpose of which is to supply gradually labels to the label lifter 48 is mounted on a rack 112 which is slidably disposed in a support 114. In order to prevent the labels from being shifted in the pile, a plurality of rods 116 is provided which are fixed to a lower platform 117 and extend vertically upwards passing through the carrier 44 and thus acting as guides therefor. The carrier may be raised and lowered by any convenient mechanism which may, if desired, be actuated from the label lifter arm 28 or from the outer conveyor 12.

The free end of the can chute 46 has a slot in its bottom so positioned as to be aligned with the root of the opener tag on the cans. This tag is laid flat or approximately so, against the cans and the purpose of the slot is to permit the tag to be bent up at right angles to the can by means of a mechanism now about to be described, so that when the can is deposited in the receptacle the tag can pierce the label and remain on the outside thereof after the labeling operation has been finished.

The tag bending mechanism as shown in Fig. 6 consists of a wheel 118 provided with an articulated claw 119 held in position by means of a spring 120 and projecting beyond the periphery of the wheel, which is rotatably mounted on a support 121 secured to the frame members 122. The tag bender wheel 118 is caused to run in synchronism with the outer conveyor 12 the movement of which is transmitted to the wheel by means of a chain 124 (Fig. 1) driving a pulley 126 (Fig. 6) which in turn drives a pulley 128 fast on the wheel shaft. The claw 119 is directed backwardly with respect to the direction of travel of the cans so that as each can moves into position its tag is engaged by said claw and bent up. To prevent the claw from remaining engaged when the tag has been bent up at right angles, a notch 130 is cut into the periphery of the wheel 118, into which the claw is adapted to be moved by the advancing can so as to clear the tag. A lateral projection 132 is provided on the wheel 118 to actuate a can stop device comprising a bar 134 projecting from a gate member 136 pivoted in front of the delivery end of the chute. The said bar extends into the path of the projection 132 so that the bar is raised once in every revolution of the wheel 118 thus lowering the gate and allowing the can to be picked up by the can lifter.

Below the chute 46 and on the side of the tag bender remote from the delivery end, there is provided a bath 138 containing a liquid adhesive and having mounted within it a rotary brush 140 so positioned as to brush the side of the cans resting on the bottom of the chute, to which end a suitable longitudinal opening is provided in the floor of the chute. On the same shaft as brush 140 but outside the bath 138 is mounted a pulley 140' which may be driven from another pulley 142 mounted on the same shaft as pulley 126.

In Fig. 7 is shown one half of one of the receptacles 144 which as seen in Fig. 1 are mounted in spaced relation on the outer conveyor 12. The other half of the receptacle is substantially the mirror image of the one shown and both halves are adjustably mounted on rods 152 so that the width of the receptacles may be changed as required. Each half receptacle consists of an angle element 146 having a horizontal arm 148 shorter than its other vertical arm 150. The horizontal arm is provided on the side thereof remote from

the vertical arm with spring clips 154 whereby the half receptacle may be detachably and slidably mounted on the rods 152. On the same side of the horizontal arm attachment fingers 156 are also provided to enable the half receptacle to be attached to the conveyor chains. The vertical arm 150 is flared outwardly at its free end and flanges 158 and 158' are provided along its vertical margins, one of the flanges 158, being coextensive with the vertical margin while the other flange 158' extends but a short distance upwardly from the horizontal arm 148. The receptacles are mounted the rods 152 crosswise of the conveyor chains and with the shorter flanges 158' facing the can chute. This arrangement coupled with the outward flaring of the free ends of the vertical arms allows the can lifter to introduce the cans easily into the space within the receptacle, the flange 158 acting as a stop and guide and the flanges 158' acting to prevent the can from tipping out of the receptacle.

The vertical arm 150 has formed in it a slot 160 through which the nose 162 of a gripper member 162a is adapted to pass. Said gripper member is pivotally mounted between lugs 163 projecting outwardly and downwardly from the angle of the half receptacle, and has a U shape tail piece 162' between the legs of which a roller 164 is rotatably mounted. A spring (not shown) normally maintains the gripper with its nose projecting through the slot 160. The rollers 164 are adapted to engage guide rails (not shown) provided along the path of the conveyor 12 and positioned so that the gripper member is moved to retract its nose from the slot 160 when the label is being deposited by the label lifter, to move its nose into operative position to hold down the label, to return to release position when the can is being deposited in the receptacle and to move again into operative position to grip the can by its projecting edge until the labeling operation has been completed. The horizontal arm 148 has also a slot 166 through which the upturned lug of the cans is adapted to project after passing through the label.

As best seen in Figs. 1 and 8, a plurality of pressure fingers 168 is mounted on the outer conveyor 12 one below each receptacle so as to be directed inwardly of the closed figure formed by said conveyor. The free end of each pressure finger has rotatably mounted on it a doubly flanged wheel 170 adapted to engage a yieldable connection consisting of springs 184 between arms 176 of a label wiper device 172 mounted on the inner conveyor 16. As shown in Fig. 8 the label wiper device comprises two pairs of arms 176 the arms of each pair being rigidly coupled together crosswise of the conveyor 16 by cross-bars 180 and the pairs so formed being pivotally mounted at one end on the inner conveyor 16, so as to be directed towards the outer conveyor 12. The free ends of the pairs of arms carry rotary wiper brushes 174 which are preferably conical in shape. Each pair of arms is normally maintained in a position substantially perpendicular to the inner conveyor 16 by means of springs 182, and as previously stated, the pairs are yieldably connected together by springs 184 extending lengthwise of the conveyor 16, and conveniently anchored to the cross-bars 180.

Referring now to Fig. 1, it will be seen that whereas the upper part of the outer conveyor 12 runs substantially horizontally, the corresponding portion of the inner conveyor 16 runs at three different inclinations indicated by the letters A, E and F, the zone A being that nearest

to the delivery end of the chute 46. These three zones correspond to three steps in the labeling operation, which takes place over the zones designated B, C and D for the outer conveyor, as will be more clearly understood from the following description of the labeling process.

As already stated, one face of the cans is coated with adhesive during their travel down the chute 46. It has also been explained that owing to the construction of the label and can transfer devices, an empty receptacle, as it moves into the horizontal or upper stretch of the outer conveyor, has deposited in it a label which is temporarily held down by the gripper nose 162. Subsequently a can is deposited on top of the label with the adhesive coated face in contact with the label. While the can is being introduced into the receptacle, the nose of the grippers 162a will have been retracted by engagement of the rollers 164 with the guide rails, and when the can is seated on the label the grippers are allowed to move into their normal position to grip the end flanges of the can by disengagement of the rollers from the guide rails. On completion of this operation, the receptacle containing the can and the label may be said to enter zones A and B. In zone B a gumming device 186 is provided comprising a tank 188 for liquid adhesive mounted above the outer conveyor 12 and having an opening in its floor through which adhesive is fed to a rotary brush 190 which rotates in a direction opposite to the rotary travel of said outer conveyor. As the receptacle with its contained can approaches the brush 190, a wiper device 172 moves along the inclined zone A so as to bring its yielding connection member 184 into engagement with the roller of the pressure finger associated with said receptacle. The arrangement is such that when the loaded receptacle is below the brush 190, so that the contained can has its face remote from the conveyor wiped by said brush to apply adhesive thereto, the conical brush 174 carried by the pair of arms 176 furthest from the delivery end of the chute, passes through the outer conveyor 12 to raise the portion 185a of the label 185. Depression of the spring 184 by pressure finger 168 urges the two pairs of arms of the wiper device towards each other and causes them to be pressed firmly but resiliently against the faces of the can facing the ends of the horizontal stretch of the outer conveyor. As both conveyors advance further, the receptacle with the can is brought into zone CE, where a second gumming device 186' having a tank 188' for liquid adhesive and a brush 190', generally identical with the gumming device 186 is installed. At this part of the travel, the wiper arms 176 will have been raised by the inclination of zone A of the inner conveyor a sufficient distance to enable the pair of wiper arms nearest to the chute 46 to have lifted the corresponding portion 185b of the label and laid it alongside the corresponding face of the can. As the receptacle and can pass under the brush 190', the projecting part of the portion 185a of the label is laid by the brush on to the face of the container which has just been coated with adhesive by the brush 190, and is itself coated on the outside with adhesive by the brush 190'. In passing from under the gumming device 186' the receptacle and the wiper device enter fully into zone E of the inner conveyor in which the inclination of the inner conveyor is away from the outer conveyor. Thus the wiper arms are gradually retracted from the can but it will be noted

that the pair of wiper arms remote from the chute descends more rapidly than the other pair so that the portion 185b of the label which has not yet been laid on the coated outer surface 5 of the portion 185a already adhered to the can, is still held pressed against the can. At the end 10 of the zone E of the inner conveyor the receptacle and can enter zone D of the outer conveyor where a rotary label wiper designated generally by the numeral 194 is provided. This device comprises a shaft 198 arranged perpendicularly to the outer conveyor 12 and driven by means of conical gears 196, 196' from a convenient shaft 196a of the driving system for the inner conveyor. On said shaft 198 is secured an arm 200 the free end of which carries a brush 202. As the shaft 198 rotates, the brush 202 is moved through a circle, the timing being such that the brush 202 engages the upper part of the upstanding portion 165b 20 of the label on the side thereof nearest to the chute 46, so that in continuing to revolve, the brush 202 lays the said upper part on the coated and adhered upper part of the portion 165a and wipes it into firm adhering contact, thus completing the labeling of the can.

After passing the shaft 198 of the gumming device 194, the wiper device 172 enters zone F of the inner conveyor which here runs at an inclination in the same sense as but greater than 30 that of zone E so as to retract the wiper device completely from the can and allow the receptacle to proceed to the end of the horizontal stretch where the labeled can is discharged, to which end it may be removed from the receptacle 35 by hand or any convenient type of discharge mechanism may be provided.

Although in the present specification and in the accompanying drawings a specific embodiment of the present invention has been described and illustrated it is to be understood that it is not limited thereto and is restricted only to the scope of the appended claims.

What I claim is:

1. A labeling machine for labeling cans, in particular cans of substantially frusto-pyramidal shape having a square base comprising a frame, an outer and an inner endless conveyor mounted on said frame and arranged to run in synchronism, said outer conveyor surrounding said inner conveyor and having a portion adjacent but non-parallel thereto, driving means on said frame for driving said conveyors, a plurality of can receptacles arranged in spaced relation along said outer conveyor, a can chute having a delivery end arranged in proximity to one end of the frame, a label holder disposed between said can chute and said frame, transfer devices located at said end of the frame and comprising a can lifter assembly and a label lifter assembly for respectively depositing a label and a can in engagement with a can receptacle, actuating means for said transfer devices, and a plurality of wiper devices including pairs of wiper brushes for embracing the cans and being mounted on the inner conveyor and directed towards the outer conveyor to successively engage and disengage the cans in said receptacles by the non-parallel movement of the adjacent portions of said conveyors.

2. A labeling machine for labeling cans, in particular cans of substantially frusto-pyramidal shape having a square base comprising a frame, an outer and an inner endless conveyor mounted on said frame, said outer conveyor surrounding said inner conveyor, driving means on said frame

for driving said conveyors in synchronism with each other, a plurality of can receptacles arranged in spaced relation along said outer conveyor, a can chute having a delivery end located in proximity to one end of said frame, said outer conveyor having a substantially straight stretch extending between the ends of the frame and said inner conveyor having a first zone inclined towards the straight stretch of said outer conveyor from the end thereof nearest to said chute to an intermediate point thereof, a second zone following immediately on said first zone oppositely inclined with respect to said first zone and forming a relatively small angle with said straight stretch and a third zone following immediately on said second zone and inclined in the same sense but at a greater angle, a label holder disposed between said can chute and said frame, transfer devices located at said end of the frame nearest to said chute and comprising a can lifter assembly and a label lifter assembly for respectively depositing a label and can in engagement with a can receptacle, actuating means for said transfer devices, a plurality of wiper devices including pairs of wiper brushes for embracing the cans and being mounted on the inner conveyor and directed towards the outer conveyor, a yieldable coupling between said pairs of wiper brushes, a pressure finger mounted on the outer conveyor below each receptacle and directed towards the inner conveyor, said pressure fingers being adapted to engage and depress said yieldable coupling to urge the wiper brushes towards each other and, adhesive applying means for applying adhesive to the cans disposed one in association with said chute, a second at substantially the end of the first zone of the inner conveyor remote from the chute, and a third at a point intermediate the end of the straight stretch nearest to the chute and the second adhesive applying means.

3. In a labeling machine for labeling cans, in particular cans of substantially frusto-pyramidal shape having a square base, comprising a frame, an outer and an inner endless conveyor mounted on said frame, said outer conveyor surrounding said inner conveyor and having a portion adjacent but non-parallel thereto, driving means on said frame for driving said conveyors in synchronism with each other, a plurality of can receptacles mounted in spaced relation on said outer conveyor, a can chute having a delivery end arranged in proximity to one end of the frame, a label holder disposed between said chute and said frame and a plurality of wiper devices mounted on said inner conveyor in spaced relation and directed towards said outer conveyor adapted to be brought into operative relation to the cans in said receptacle by the non-parallel movement of the adjustable portions of said conveyors, transfer devices for transferring labels from the label, holder and cans from the chute to said receptacles, said transfer devices comprising a slotted lifter arm, securing means for securing said lifter arms, slidably and swingingly to said frame, a pivoted arm pivotally secured to said frame, a link connecting the free ends of the two arms, lifting means attached to said lifter arm and actuating means adapted to be driven in synchronism with the conveyors for actuating said lifter arm.

4. In a labeling machine for labeling cans, in particular cans of substantially frusto-pyramidal shape having a square base, comprising a frame, an outer and an inner endless conveyor mounted

on said frame, said outer conveyor surrounding said inner conveyor and having a portion adjacent but non-parallel thereto, driving means on said frame for driving said conveyors in synchronism with each other, a plurality of can receptacles mounted in spaced relation on said outer conveyor, a can chute having a delivery end arranged in proximity to one end of the frame, a label holder disposed between said chute and said frame and a plurality of wiper devices mounted on said inner conveyor in spaced relation and directed towards said outer conveyor adapted to be brought into operative relation to the cans in said receptacle by the non-parallel movement of the adjustable portions of said conveyors, transfer devices for transferring labels from the label holder and cans from the chute to said receptacles, said transfer devices comprising a slotted lifter arm, securing means for securing said lifter arms, slidably and swingingly to said frame, a pivoted arm pivotally secured to said frame, a link connecting the free ends of the two arms, lifting means attached to said lifter arm and actuating means including a crank driven from the outer conveyor and, a coupling rod and a cross head connecting the crank to said lifter arm on the side of the securing means remote from the link for causing the lifter arm to swing between two end positions one of which is over the outer conveyor, the arrangement being such that when the lifter arm reaches its end position over the conveyor the lifting means is brought over one of said receptacles.

5. In a labeling machine for labeling cans, in particular cans of substantially frusto-pyramidal shape having a square base, comprising a frame, an outer and an inner endless conveyor mounted on said frame, said outer conveyor surrounding said inner conveyor and having a portion adjacent but non-parallel thereto, driving means on said frame for driving said conveyors in synchronism with each other, a plurality of can receptacles mounted in spaced relation on said outer conveyor, a can chute having a delivery end arranged in proximity to one end of the frame, a label holder disposed between said chute and said frame and a plurality of wiper devices mounted on said inner conveyor in spaced relation and directed towards said outer conveyor adapted to be brought into operative relation to the cans in said receptacle by the non-parallel movement of the adjustable portions of said conveyors, transfer devices for transferring labels from the label holder and cans from the chute to said receptacles, said transfer devices comprising a slotted lifter arm, securing means for securing said lifter arms, slidably and swingingly to said frame, a pivoted arm pivotally secured to said frame, a link connecting the free ends of the two arms, lifting means attached to said lifter arms and comprising a suction element, means for connecting said suction element to a source of suction, a support rotatably connecting the suction element to the lifter arm, and actuating means adapted to be driven in synchronism with the conveyors for actuating said lifter arm.

6. In a labeling machine for labeling cans, in particular cans of substantially frusto-pyramidal shape having a square base, comprising a frame, an outer and an inner endless conveyor mounted on said frame, said outer conveyor surrounding said inner conveyor and having a portion adjacent but non-parallel thereto, driving means on said frame for driving said conveyors in syn-

chronism with each other, a plurality of can receptacles mounted in spaced relation on said outer conveyor, a can chute having a delivery end arranged in proximity to one end of the frame, a label holder disposed between said chute and said frame and a plurality of wiper devices mounted on said inner conveyor in spaced relation and directed towards said outer conveyor adapted to be brought into operative relation to the cans in said receptacle by the non-parallel movement of the adjustable portions of said conveyors, transfer devices for transferring labels from the label holder and cans from the chute to said receptacles, said transfer devices comprising a slotted lifter arm, securing means for securing said lifter arm slidably and swingingly to said frame, a pivoted arm pivotally secured to said frame, a link connecting the free ends of the two arms, suctional lifting means attached to one of said lifter arms and comprising a hollow body portion having a connection branch projecting laterally therefrom and adapted to be connected to a source of suction, a first suction mouth at one end and a co-planar second suction mouth at the other end, a guide bar projecting from said body portion substantially perpendicularly to the plane of the mouths, a stop-collar adjustably secured to said guide bar, a support rotatably connecting the suctional lifting means to the lifter arm and having a perforated head slidably embracing the guide bar, a pair of pins projecting from the body portion in coaxial alignment, carrying rotary rollers and located above the second mouth, a guide way having a base hingedly connected to the frame, a pair of parallel leg portions projecting from said base and having guide surfaces extending from the free ends of said leg portions to a point spaced from said base to provide an opening adapted to allow the pins to pass freely therethrough and actuating means adapted to be driven in synchronism with the conveyors for actuating said lifting devices.

7. In a labeling machine for labeling cans, in particular substantially frusto-pyramidal cans with a square base, having a tag on one wall for subsequent opening of the can, comprising a frame, an outer and an inner endless conveyor mounted on said frame, said outer conveyor surrounding said inner conveyor and having a portion adjacent but non-parallel thereto, driving means on said frame for driving said conveyors in synchronism with each other, a plurality of can receptacles mounted in spaced relation on said outer conveyor, a plurality of wiper devices mounted in similar spaced relation on said inner conveyor and directed towards said outer conveyor adapted to be brought into operative relation to the cans in said receptacle by the non-parallel movement of the adjustable portions of said conveyors, a label holder disposed adjacent one end of said frame, a can chute having a slotted delivery end located on the side of said holder remote from the frame, transfer devices for transferring labels from said holder and cans

from said chute to said receptacles and actuating means for said transfer devices, tag upsetting means comprising a wheel rotatably mounted below the slot on said chute and carrying a spring-biased articulated claw adapted to engage the tags on the cans and set them up, a notch in said wheel to allow the claw to disengage the up-set tag and driving means for driving the tag upsetting means in synchronism with the conveyors.

8. In a labeling machine for labeling cans, in particular cans of substantially frusto-pyramidal shape having a square base comprising a frame, an outer and an inner endless conveyor mounted on said frame, said outer conveyor surrounding said inner conveyor, driving means on said frame for driving said conveyors in synchronism with each other, a plurality of can receptacles arranged in spaced relation along said outer conveyor, a can chute having a delivery end located in proximity to one end of said frame, said outer conveyor having a substantially straight stretch extending between the ends of the frame and said inner conveyor having a first zone inclined towards the straight stretch of said outer conveyor from the end thereof nearest to said chute to an intermediate point thereof, a second zone following immediately on said first zone oppositely inclined with respect to said first zone and forming a relatively small angle with said straight stretch and a third zone following immediately on said second zone and inclined in the same sense but at a greater angle, a label holder disposed between said can chute and said frame, transfer devices located at said end of the frame nearest to said chute and comprising a can lifter assembly and a label lifter assembly, actuating means for said transfer devices, a plurality of wiper devices including pairs of wiper brushes mounted on the inner conveyor and directed towards the outer conveyor, a yieldable coupling between said pairs of wiper brushes, a pressure finger mounted on the outer conveyor below each receptacle and directed towards the inner conveyor, said pressure fingers being adapted to engage and depress said yieldable coupling to urge the wiper brushes towards each other, adhesive applying means for applying adhesive to the cans disposed one in association with said chute, a second at substantially the end of the first zone of the inner conveyor remote from the chute, and a third at a point intermediate the end of the straight stretch nearest to the chute and the second adhesive applying means, and label wiper means positioned at a point of the third zone and comprising a shaft adapted to be driven from the conveyor driving means, an arm fast on said shaft extending across the outer conveyor and spaced therefrom on the side thereof remote from the inner conveyor, and a brush on the free end of the shaft adapted to engage the extremity of a label on the side thereof nearest to said chute to wipe said extremity onto the can.
